HYDRAULIC APPARATUS

Joseph J. Warner, Medford, Mass.

Application September 26, 1939, Serial No. 296,604

2 Claims. (Cl. 60—54.6)

This invention relates to hydraulic apparatus wherein controlling or regulatory impulses are necessarily given at some distances from the location of the mechanism performing the work.

One of the most serious defects in hydraulically operated mechanisms has been that variations in the volume of the liquid in the apparatus due to temperature changes are likely to impair the accuracy of the apparatus. Another serious obstacle has been the constant danger that air may become entrapped with the liquid and result in uneven and variable transmission of effective pressure. Accordingly, one object of my invention is to eliminate inaccuracies in the operation of hydraulic apparatus resulting from changes in the volume of the liquid, thereby adapting apparatus constructed according to my invention for use in vessels and aircraft where sudden and violent temperature changes are frequently encountered.

Another object of my invention is to provide means for drawing off any air which may become entrapped with the liquid in a hydraulic apparatus.

An important feature of my invention resides in a combination of valves and conduits by means of which entrapped air can be withdrawn from the fluid, the combination of valves and conduits also serving to by-pass liquid from one side of the apparatus to the other to eliminate pressure differentials and to permit resetting of the controlling means relative to the work performing mechanism.

An important field of use for my invention is in marine steering gears in which rotation of the steering wheel is arranged to deliver hydraulic impulses to the rudder or rudders. For purposes of illustration I shall describe my invention as applied to a marine steering gear, although it will be obvious to those skilled in the art that my invention can be profitably employed in many other fields.

These and other objects and features of my invention will be more readily understood and appreciated from the following detailed description of a preferred embodiment thereof adapted to steer a vessel and shown in the accompanying drawings in which,

Fig. 1 is a schematic plan view of a hydraulic steering system constructed according to my invention,

Fig. 2 is a view in front elevation of the controlling apparatus,

Fig. 3 is a view in cross section along the line 3—3 of Fig. 2,

Fig. 4 is a view in cross section along the line 4—4 of Fig. 3,

Fig. 5 is a view in cross section taken vertically through the work performing mechanism,

Fig. 6 is a view in cross section along the line 6—6 of Fig. 5,

Fig. 7 is a view in cross section along the line 7—7 of Fig. 5,

Fig. 8 is a view in cross section along the line 8—8 of Fig. 5, and

Fig. 9 is a view in cross section along the line 9—9 of Fig. 5.

The general combination and arrangement of the elements forming my invention is best shown in Fig. 1 where it will be apparent that a fluid-tight housing 10 having opposed cylinders 28 and 29 is associated with a steering wheel 13. These elements are designed to be located in the forward part of a vessel, or in the wheel house, and are connected by conduits 39 and 40 to cylinders 44 associated with a fluid-tight housing 46 disposed adjacent the rudder post in the stern of the vessel.

The details of the control mechanism are shown in Figs. 2—4 where it will be seen that the fluid-tight housing 10 provides bearings for a transverse shaft 12 operating inside a sleeve 15 and carrying at its outer end a conventional steering wheel 13. Keyed on the shaft 12 inside the housing 10 is a pinion 16 which meshes with a large gear 18 keyed to a sleeve loosely carried by a stud 17 screwed into the rear wall of the housing 10. Also keyed to the sleeve on the stud 17 is a pinion 20 which meshes with the teeth of a rack 26 supported from below by a self-adjusting guide block 24 carried on a stud 22 screwed into the rear wall of the housing 10 in vertical alignment with the stud 17 and shaft 15. Screwed into the side walls of the housing 10 is a pair of oppositely disposed cylinders 28 and 29 which enclose pistons 30 carried on the ends of the rack 26. At the outer end of each piston 30 is a cup 32 of leather or other tough flexible material held against the outer surface of each piston by a washer 34 and a screw 36 which also serves to secure the piston to the end of the rack.

Threaded on the ends of the cylinders 28 and 29 are cap fittings 38 each of which has an angular passage. Tapped into the bottom of the fittings 38 are metal pipes or conduits 39 and 40 which serve as the pressure lines of the hydraulic system. As will be seen from an inspection of Fig. 1, the lines 39 and 40 lead rearwardly in the vessel to the work performing mechanism of the system, and it will be ob-

served that a crossover is effected, that is to say, the line 38 which leads from the left-hand cylinder 28 goes to the right-hand end of the work performing mechanism and that pressure line 40 which leads from the right-hand cylinder 28 goes to the left side of the work performing mechanism.

The work performing mechanism is similar to the controlling mechanism in its general features. It consists of a pair of oppositely disposed cylinders 44 provided at their outer ends with cap fittings 42 into the top of which the pressure lines 38 and 40 are led in the manner stated above. The inner ends of the cylinders 44 are screwed into the side walls of a metal housing 46 which lies in a horizontal plane in contrast with the housing 10 of the controlling mechanism which is in a vertical position. A rack 48 operates in the housing 46 and in the cylinders 44, being guided in its movement by a block 50 carried on a stud 52 screwed into the bottom of the housing 46. On each end of the rack 48 is a piston 54 provided with a leather cup 56 secured to the outer end of each piston by a washer 57 and a screw 58 which does not, however, enter the rack 48. The ends of the rack are reduced and mounted to slide in apertures in the pistons 54. The pistons 54 are slotted as shown in Fig. 8 and locking pins 60 passed through the ends of the rack 48 operate in the slots in the pistons 54, thus allowing limited relative longitudinal movement between the rack and the pistons. Powerful coil springs 62 encompass the reduced portion of the rack 48, the inner ends of the pistons 54 being recessed to provide a tubular skirt for housing them. Heavy washers 64 serve to back up the springs 62, and it will be apparent that the springs 62 urge the pistons 54 outwardly on the rack 48.

In mesh with the teeth of the rack 48 and within the housing 46 is a large gear 66 which is keyed to a vertical shaft 68 journaled in the housing 46 and extending up through the upper wall thereof. Rigidly secured to the upper end of the shaft 68 is an arm 70 which is pivotally connected at its outer end to an elongated link 72. The link 72 is pivotally connected to a tiller 74 which in turn is rigidly secured to the rudder post 18 as shown in Fig. 1.

The operation of the parts thus far described can be briefly stated. The entire system including the housings 10 and 46 is filled with oil or other liquid suitable for use in an hydraulic system, and when this has been done, it will be apparent that if the wheel 13 is rotated in counter-clockwise direction, the piston 30 in the cylinder 29 will be moved outwardly, toward the left, forcing oil through the line 39 and into the right-hand cylinder 44 where the piston in the cylinder will be forced inwardly, moving the rack 48, rotating the gear 66, and moving the arm 70 to the left, thus swinging the tiller 74 to the left and causing the vessel to swing to the left. If the wheel 13 is rotated in clockwise direction the piston, the cylinder 28 will force oil through the line 40 to actuate the rack 48 and the gear 66 which will, in the manner already described, swing the tiller 74 to the right, thus swinging the vessel in the same direction.

As shown in Fig. 9 each of the cap fittings 42 is provided at its upper end with a small passage 80 leading from the cylinder to the pressure line and serving to remove air entrapped in the top of the cylinder. It is contemplated that the work performing mechanism will be located near the

rudder post and lower down than the control mechanism. Therefore any air entrapped in the ends of the cylinders 44 or in pressure lines 39 and 40 will rise and enter the fittings 38 on the ends of the cylinders 28 and 29. Each of the fittings 38 is provided with a small passage 82 into which is threaded a valve 84. Threaded into the valves 84 are by-pass pipes 86 which join in a T-shaped union 88 from which leads an outlet 90. The other end of the outlet 90 passes into a valve 92 which leads into the housing 10. The housing 10 is provided with a removable filling plug 11 having a small passage or jet 94 communicating with the outside of the housing. It will now be apparent that if in the course of operation the system should build up more pressure on one side than the other, the valves 84 can be opened and the by-pass 86 will allow the pressures to equalize. If there is air in the system the valve 92 can also be opened, and since it is in direct communication with the lines 39 and 40 and is the highest point in the conduit system, the entrapped air will rise and pass through the lines 86 into the outlet 90, through the valve 92 into the housing 10 and out through the passage 94 in the fill plug 11. It will also be evident that the easiest way to fill the system with oil or other liquid is to open the valves 84 and the valve 92 so that the liquid will flow directly into the lines 39 and 40 as well as into the housing 10. The housing 46 is provided with a filling plug 76 and can be filled directly.

It should be observed that the function of the leather cups 56 and 32 is to act as one-way valves. That is to say, when a piston is being pushed outwardly in a cylinder its associated leather cup will open and prevent the passage of liquid by the piston. When the piston is being withdrawn into the cylinder the cup will tend to fold up so that some liquid can flow past the piston from within the housing. The leather cups, therefore, insure smooth and efficient operation since all of the pressure exerted by a piston in its outward stroke will be utilized whereas pressure behind the piston will not interrupt its inward movement by reason of the fact that a back pressure can be relieved by the passage of liquid by the piston and its associated leather cup. It is important to note that both the housing 10 and the housing 46 are designed to be entirely filled with the hydraulic fluid, a feature which materially reduces the likelihood of air becoming entrapped in the system.

In particular, it is to be noted that in a heavy sea a wave often slams against the rudder pushing it to one side and thus moving the pistons in the cylinders 44 and spinning the steering wheel. If the housing 46 were not filled with fluid, air would be sucked into the one of the cylinders 44 whenever a wave hit the rudder, thus hindering the smooth accurate operation of the system, since part of the air would work by the leather cups and into the pressure lines.

The combination of the locking pins 60, the slots in the pistons 54, and the springs 62 operates to compensate for changes in the volume of the liquid in the system due to changes in temperature. That is to say, a reduction in the volume of the liquid due to cold weather will cause the fluid in the housings 10 and 46 to pass by the leather cups on the ends of the pistons, whereas an increase in the volume of the liquid due to hot weather will press the pistons 54 inwardly in the cylinders 44 and compress the spring 62, it being understood that the liquid in the con-

duits 39 and 40 is much more subject to expansion and contraction due to its surface area than the liquid in the body of either of the housings.

The particular advantages resulting from the use of my invention arise because I have reduced the possibility of entrapped air by filling both housings with fluid and arranged for its escape through the conduits 86 and 90, the fact that pressure differentials can be eliminated by opening the valves 84, and because I have provided means which compensate for any changes in the volume of the liquid in the system.

It should further be understood that by opening the valves 84 and moving the tiller 74 until it is parallel with the longitudinal axis of the vessel, the relative positions of the rudder and the pistons can be set, thus allowing the king spoke of the steering wheel to be set vertically when the rudder is in normal position and insuring equal movement thereof in either direction.

While the invention has been described as applied to apparatus for steering vessels, it must be understood that with very slight modifications the system shown in the drawings can be adapted to control the rudder and ailerons of an airplane. It can also be adapted to steer an automobile or truck or, indeed, it is useful wherever it is desirable to separate work performing mechanism from controlling mechanism. The system illustrated in the drawings may, with slight modifications, be operated to control valves of a large automatic pressure pump in order to steer a heavy vessel or ship where power is necessary to move the rudder.

Having thus disclosed my invention what I claim as new and desire to secure by Letters Patent of the United States is:

5. 1. In a hydraulic system, a housing, a pair of cylinders secured in the walls of said housing, a rack disposed in the housing and having reduced shouldered ends extending into said cylinders, a pin secured in each of said reduced ends, a piston in each cylinder having a central longitudinal bore receiving the end of the rack and a slot accommodating the pin, the inner end of each piston being provided with a tubular skirt, a spring disposed within the skirt of each piston and surrounding a portion of the reduced end of the rack, and a washer surrounding the reduced end of each rack and held against the shoulder on the rack.
10. 2. In a hydraulic steering system for vessels, a housing, a pair of cylinders secured in the walls of said housing, a rack disposed in the housing and having ends extending into said cylinders, a pin secured in each of said ends, a piston in each cylinder having a longitudinal bore receiving the end of the rack and a slot accommodating the pin, the inner end of each piston being provided with a tubular skirt, and a spring disposed within the skirt of each piston and surrounding a portion of the end of the rack, whereby expansion of fluid in the system is compensated for by the opposite movement of the pistons without changing the position of the rack.
15. 30. JOSEPH J. WARNER.
